UNITED STATES PATENT OFFICE.

PETER L. WILBUR, OF TUCKAHOE, NEW YORK.

SPRAYING APPARATUS.

Application filed April 16, 1921. Serial No. 461,845.

To all whom it may concern:

Be it known that I, PETER L. WILBUR, a citizen of the United States, and a resident of Tuckahoe, in the county of Westchester and State of New York, have invented certain new and useful Improvements in Spraying Apparatus, of which the following is a specification.

This invention relates to a spraying device which may be used as a fire extinguisher or a sprayer for various uses in which a stream of liquid is ejected from a container or reservoir by pressure, such as fluid pressure, applied to the liquid in the container, or by a reduction of pressure in the container by withdrawing and discharging the liquid from the container by a pump, the present application being a continuation in part of my co-pending application Serial No. 402,922, and it is an object of the invention to provide improved means to connect the outlet of the container with the liquid in the container near the side and end which is lowermost in all positions of the container.

It is a further object of the invention to provide an improved and novel arrangement of combined pump and liquid container to discharge the liquid from the container, and of means to connect the pump with the liquid in the lowermost part of the container in all positions thereof.

It is another object of the invention to provide an improved pump structure and means to close the pump outlet when the device is not in use.

Another object of the invention relates to means connected to the container which is adapted to releasably engage a support for the device.

Other objects and advantages will herein-after appear.

In the drawings accompanying and forming a part of this specification, Figure 1 is an end elevation, partly broken away to show the arrangement of the intake to the outlet of the container.

Figure 2 is a side elevation, partly in section, showing the arrangement and construction of the container or casing together with the mounting therein of an intake to the outlet and the connection of the latter with the pumping mechanism.

Figure 3 is an end elevation looking at the end opposite to that shown in Figure 1 showing the container arranged with means

to releasably connect the container to a support and the arrangement of the mounting of pumping mechanism upon the container, said pumping mechanism being partly in section to show the connections for controlling the entrance and discharge of liquid from the pump cylinder.

Figure 4 is a perspective view of the container sections showing them in disassembled relation.

Figure 5 is a sectional view of the portion of the pump containing the discharge outlet to show the arrangement of the valve mechanism to control the discharge of the liquid from the pump chamber, the parts being shown in the positions they assume when liquid is being drawn to the pump chamber in front of the piston, said parts being shown enlarged in relation to Figure 1.

Figure 6 is a view similar to Figure 5, but showing the positions the parts assume when liquid is being discharged from the pump chamber in front of the piston.

Figure 7 is a view similar to Figure 5 but showing the positions of the parts when the piston is in its innermost position and the discharge outlet closed.

Figure 8 is an enlarged view in perspective of a valve chamber to which the discharge nozzle is connected showing the arrangement of ports thereto to control the discharge of liquid from the pump chamber therethrough.

Figure 9 is an enlarged perspective view of the valve supports to control the inlet and outlet of liquid from the pump chamber.

Figure 9^a is an enlarged perspective view of the valves for controlling the inlet and outlet of liquid from the pump chamber.

Figure 10 is an enlarged perspective view of the discharge nozzle for the pump.

Figure 11 is an enlarged perspective view, partly in section, of a valve to control the outlet of the liquid from one end of the pump chamber and to control the discharge of the liquid from the pump and a spring to co-operate with said valve.

Figure 12 is an enlarged view in perspective of a portion of the pumping mechanism and the intake from the container to show the connection of the latter with the pumping mechanism.

Figure 13 is an enlarged sectional view taken substantially on the line 13—13 of

Figure 12 to show the connection of the intake from the container with the pumping mechanism and showing by arrows the flow of liquid therethrough from the pumping mechanism.

Figure 14 is an enlarged detail view in section to show the means and manner of locking the pump piston against movement in its innermost position.

Figure 15 is a sectional plan view looking at the top of Figure 14 and showing the means to releasably mount the device upon a support.

Figure 16 is a longitudinal sectional view of a closure plug for the filler opening of the container arranged with a valve controlled port to permit the entrance of air to the container and prevent the creation of a vacuum therein as the liquid is discharged from the container.

Figure 16^a is a plan view of the closure plug.

Figure 17 is a perspective view of the means connected to the container to releasably connect the same to a support and showing the same in operative relation to such a support.

Figure 18 is a longitudinal sectional view taken on the line 18—18 of Figure 17.

Figure 19 is a sectional detail view showing a modification of the valve mechanism to control the inlet and outlet of the liquid from the pump chamber;

Figure 20 is an enlarged sectional detail view to show the manner of connecting the ports of the pump cylinder with the means to connect said ports with the container and the discharge outlet of the pump; and

Figure 21 is a sectional detail view showing a modification of the discharge nozzle and valve mechanism for controlling the flow of liquid to one end of the cylinder and the discharge of liquid from the opposite end of the cylinder to the discharge nozzle.

Similar characters of reference designate like parts throughout the different views of the drawings.

The embodiment of my invention shown in the drawings comprises a container or reservoir (designated in a general way by C), preferably shallow and of circular shape, that is it is of greater diameter than length, consisting of a pair of sections 21, 22 (Figure 4) to have mating connection as a cover and a receptacle, the one section 21 being arranged with concentric depressed portions 23, 24 in the end to provide an annular rounded or beaded portion 25 and an annular bead 26 within the bead 25 to serve as reinforcing ribs to add rigidity to the structure and lessen the possibility of denting should the container be dropped. The section 21 engages over the section 22 to about a peripheral bead 27 as shown in Fig-

ure 2 and limit the connecting movement of the sections, the sections being connected in such position in a suitable manner as by soldering or otherwise. The section 22 has a depressed portion 28 of partially circular form extending transversely and axially thereof with an opening 29 in such depressed portion axially of the container to constitute the outlet of the container. The section 21 has a perforation 30 to constitute the filler opening for the container having a screw threaded flanged member 31 for the application of a closure plug 32.

To connect the outlet opening 29 with the liquid in the container in the lowermost portion in all positions thereof an intake is provided for said outlet arranged to assume a position by gravity to position an inlet to the intake near the side portion and end of the container which is lowermost.

This intake comprises a pair of rigid tubes 33, 33', the tube 33 being carried by a sleeve 34 in liquid connection with an enlargement 35 of said sleeve, said sleeve being rotatably mounted on a stud 36 supported axially of the container with a port or ports 37 in the lateral wall thereof in communication with the enlargement 35 of the bore of the sleeve forming an annular chamber around said stud, said bore leading to a passage 38 in the stud having an outlet at the end in the opening 29 of the container (Figures 2 and 18). The tube carrying sleeve 34 is confined between the end wall of the container section 21 and a collar 39 fixed on the stud and to prevent undue metal to metal contact felt washers 40 are interposed between the ends of the sleeve and the container wall 21 and collar 39.

The tubular section 33' is coupled in fluid connection with the tubular section 33 and to have universal movement relative thereto. For this purpose a hollow plug or casing 41, shown of triangular shape in cross section, is coupled in liquid connection with the tube 33 by a member 42 fixed to the end of said tube and upon which the casing 41 is mounted as at 43 to rotate on an axis parallel with the axis of rotation of the tube carrying sleeve 34. The tube 33' is coupled in liquid connection with the casing 41 by a member 44 fixed to the end of the tube 33' and rotatably mounted in the casing, as at 45, to rotate on an axis transverse to the axis of rotation of the casing on the coupling member 42. The tube 33' extends to adjacent the side of the reservoir with the end open and is adapted to position such inlet by gravity near the side of the container below the axis of the intake supporting stud 36, such movement being facilitated by a weight 46 fixed to the section of the intake 33'.

By the arrangement of the universal coupling of the intake sections the tube 33' is also adapted to assume a position by gravity to position an inlet to the intake near the side portion and end of the container which is lowermost.

The tube 33' is coupled in liquid connection with the tube 33 by a member 42 fixed to the end of said tube and upon which the casing 41 is mounted as at 43 to rotate on an axis parallel with the axis of rotation of the tube carrying sleeve 34. The tube 33' is coupled in liquid connection with the casing 41 by a member 44 fixed to the end of the tube 33' and rotatably mounted in the casing, as at 45, to rotate on an axis transverse to the axis of rotation of the casing on the coupling member 42. The tube 33' extends to adjacent the side of the reservoir with the end open and is adapted to position such inlet by gravity near the side of the container below the axis of the intake supporting stud 36, such movement being facilitated by a weight 46 fixed to the section of the intake 33'.

By the arrangement of the universal coupling of the intake sections the tube 33' is also adapted to assume a position by gravity to position an inlet to the intake near the side portion and end of the container which is lowermost.

The tube 33' is coupled in liquid connection with the tube 33 by a member 42 fixed to the end of said tube and upon which the casing 41 is mounted as at 43 to rotate on an axis parallel with the axis of rotation of the tube carrying sleeve 34. The tube 33' is coupled in liquid connection with the casing 41 by a member 44 fixed to the end of the tube 33' and rotatably mounted in the casing, as at 45, to rotate on an axis transverse to the axis of rotation of the casing on the coupling member 42. The tube 33' extends to adjacent the side of the reservoir with the end open and is adapted to position such inlet by gravity near the side of the container below the axis of the intake supporting stud 36, such movement being facilitated by a weight 46 fixed to the section of the intake 33'.

By the arrangement of the universal coupling of the intake sections the tube 33' is also adapted to assume a position by gravity to position an inlet to the intake near the side portion and end of the container which is lowermost.

The tube 33' is coupled in liquid connection with the tube 33 by a member 42 fixed to the end of said tube and upon which the casing 41 is mounted as at 43 to rotate on an axis parallel with the axis of rotation of the tube carrying sleeve 34. The tube 33' is coupled in liquid connection with the casing 41 by a member 44 fixed to the end of the tube 33' and rotatably mounted in the casing, as at 45, to rotate on an axis transverse to the axis of rotation of the casing on the coupling member 42. The tube 33' extends to adjacent the side of the reservoir with the end open and is adapted to position such inlet by gravity near the side of the container below the axis of the intake supporting stud 36, such movement being facilitated by a weight 46 fixed to the section of the intake 33'.

tion by gravity to position the inlet thereto near the end of the container which is lowermost. By this arrangement the outlet of the container is maintained in communication with or immersed in the liquid in the lowermost part of the container in all positions thereof and out of communication with the fluid pressure should fluid pressure be utilized in the container for expelling the liquid therefrom, and said intake may be utilized as an intake to the pumping mechanism to eject the liquid from the container to maintain the pumping mechanism in communication with the liquid in the lowermost part of the container in all positions thereof. Furthermore, by this arrangement of intake should the wall of the container be dented, as shown for instance in dotted lines at 47 in Figure 1, such dent would not obstruct the free movement of the intake in the container.

To eject the liquid from the container pumping mechanism is provided mounted on the exterior of the container or casing in the recessed portion 28 to extend transversely of the axis of the container and fixed in position as by soldering as shown at 48, and a plate 49 fixed to the container at the outer side of the pumping mechanism to serve as a protection therefor and for a further purpose hereinafter set forth. This pumping mechanism comprises a piston chamber or cylinder 50 having a perforated plug 51 at one end and a plug 52 at the opposite end having a recess with a discharge nozzle 52' secured therein to form a chamber 50', a port 53 in line with the orifice of the discharge nozzle communicating with the adjacent end of the pump cylinder. The pump cylinder has inlet ports 54, 55 at opposite ends, the port 55 communicating with the cylinder through a passage 56 formed by a recess in the outer wall of the plug 52 and the cylinder. These ports are connected to the outlet 29 of the container and through the intake with the liquid in the container by a tube 57 to lie contiguous to the pump cylinder and having ports in communication with the inlet ports of the cylinder by turning the metal about the wall of the inlet ports to the cylinder over the edge of the wall of the ports in the tube, as shown at 58 in Figure 20. The tube 57 has an inlet port 59 connected to the outlet 29 of the container through a passage 60 formed by a dished plate 61 having an opening for the engagement of the stud 36 and secured thereto and soldered to the piston cylinder and tube 57 over the inlet port to said tube forming a passage 60 for the flow of liquid through the stud to the inlet of tube 57. The longitudinal depressed portion 28 has a recessed portion 62 (Figures 1, 2 and 4) for the engagement of such dished plate 61. A piston 63 is reciprocated in the cylinder by a rod 64

passing through the plug 51 and a stuffing box carried by said plug to the exterior of the cylinder, and has an operating handle fixed to the outer end. The flow of liquid from the container to the cylinder through the tube 57 is controlled by suction valves through the reciprocation of the piston. These valves may be of any well known structure and as shown in Figures 3, 5, 6, 7, and 9^a comprise a valve head 65 carried by a stem 66 (Figure 9^a) slidably mounted in a tubular projection 67 of a closure plug 68 for the ends of the tube. These valves co-operate with valve seats 69 interposed in the tube between the inlet and outlet ports thereto and in the present instance are arranged by restricting the passage in the tube by annularly depressing the wall of the tube as clearly shown in the drawings.

The liquid is discharged from the pump cylinder in back of the piston through a port 70 and a registering port in a tube 71 and through said tube through registering ports in the cylinder, tube and plug 52, as shown at 72, communicating with the chamber in the plug 52 and from said chamber through the discharge nozzle. The discharging of the liquid from said end of the cylinder is controlled by a valve 73 constructed similarly to the suction valves, and slidably carried by a plug 74 to close one end of the tube, the opposite end of the tube being closed by a plug 75.

The liquid from the pump cylinder in front of the piston is discharged into the chamber of the plug 52 through a valve 76 (Figure 11) in said chamber, said valve having a tubular portion 77 slidably engaging in said port with the bore of the tubular portion opening into the cylinder, and said bore being in communication with the chamber through a port or ports 78 in the lateral wall of the tubular portion of the valve. This valve is normally urged to position with an annular enlargement 79 of the valve to co-operate with a valve seat at the port 53 and with the lateral ports 78 in the valve closed by the wall of the port 53 by a spring 80 (Figure 5). This valve also serves to close the discharge orifice in the nozzle when the piston is in its innermost position to prevent leakage of the liquid from the container through the pump and nozzle when the device is not in use (Figure 7). For this purpose, the end of the valve opposite to the tubular portion has a reduced portion with a tapered end as shown at 81 to cooperate with the valve seat formed at the inner end of the discharge orifice of the nozzle. As the piston is moved to its innermost position it will yieldingly engage the valve 76 through a spring 81 carried in an enlarged portion of the bore of the tubular portion of the valve and interposed between the valve and piston and thereby move the valve 76

against the action of the spring as clearly shown in Figure 7.

In Figure 19 I have shown a modified form of the valves to control the ingress of the liquid to and the egress of the liquid from the piston chamber, said valve consisting of a ball 82 normally yieldingly urged to a seat by a spring 83.

To lock the piston in its innermost position with the valve 76 closing the discharge orifice in the nozzle a collar 84 (Figures 14 and 15) is secured to the piston, said collar having a segmental lateral flange 85 which is adapted to engage beneath a locking member 86 carried at the end of the pumping mechanism, and shown as mounted upon the closure plug for the tube 71 by a screw 87. This collar 84 has an enlarged portion with packing therein to co-operate with the plug 51, as shown at 88, to seal the piston rod when the device is not in use. The locking member 85 is so arranged on the piston rod that when it is in locking position the handle of the rod will extend in a plane substantially with the circumferential wall of the container so as not to project beyond the end thereof.

In operation as the piston is moved outward, as indicated by the arrow in Figure 5, the suction valve 65 at the end of the tube 57 adjacent the discharge nozzle is unseated drawing liquid from the container through the intake means to the piston cylinder in front of the piston through port 55 and passage 56. As the piston is moved into the cylinder in the direction indicated by the arrow in Figure 6 the suction valve 65 at the end of the tube 57 adjacent the piston operating handle will be unseated and liquid drawn to the piston cylinder in back of the piston, the suction of the piston also operating to seat the valve 73. During this movement of the piston the liquid previously drawn into the cylinder in front of the piston operates to maintain the valve 65 controlling the flow of liquid to the front of the piston closed, the pressure of the liquid upon the valve 76 moving said valve against the action of spring 80 until the lateral ports 78 are uncovered and in communication with the chamber in the plug 52, the liquid being discharged through the tubular portion 77 of such valve and the lateral ports 78 into the chamber of plug 52 and out through the discharge orifice of the nozzle. On the successive reversed movement of the piston the operation of drawing the liquid to in front of the piston is repeated, the outlet port 53 from in front of the piston being closed by the valve 76 through the influence of the spring 80, the pressure of the liquid in back of the piston seating the valve 65 in the tube 57 at the piston operating handle end, the liquid being discharged through the registering ports 70

against the action of the spring as clearly into tube 71 unseating valve 73 and discharging the liquid from said tube through ports 72, into the chamber of the plug 52 and out through the discharge orifice of the nozzle, and such operations are repeated during the reciprocation of the piston.

The protecting plate 49 for the pumping mechanism is also arranged to releasably engage a support to support the device therefrom. For this purpose the plate is arranged as a slide by pressing the metal of the plate, as shown at 90 in Figures 3, 15 and 17, to form ribs 91 at opposite side portions to extend longitudinally of the pump and converging from the piston operating handle end of the pump to the discharge nozzle end as clearly shown in Figure 3, said plate thereby serving as a hanger to co-operate with a supporting bracket in the form of a plate 92 (Figures 15, 17 and 18) bent to form longitudinal recesses 93 to correspond to the shape and for the engagement of the ribs 91 and adapted to be secured to a suitable support, such as a wall, by screws passing through a lateral projecting portion of the bracket as shown at 94. To prevent accidental displacement of the device in the support 92 means are provided to lock the device in the support which locking means automatically locks the device in the support as it is placed therein and is releasable by a predetermined force applied to the device to remove it from the support. This locking means comprises a spring detent or latch 99 fixed at one end to the outer side of the supporting plate 92 with the free end arranged to pass through an opening in the supporting plate and engaging in and with the walls of an opening in the plate 49, as clearly shown at 100 in Figures 15 and 17.

To permit the entrance of air into the container as the liquid is discharged therefrom by the pump to displace the discharged liquid and prevent the creation of a vacuum in the container an air vent is provided. This vent in the present instance is arranged in the closure plug 32 for the filler opening, a transverse port 95 (Figure 16) in the portion of such closure arranged to be at the exterior of the container when the closure is applied to the filler opening communicates with a port 96 leading into the container, said latter port being normally closed by a valve 97 in a recess in the closure plug and urged to position to close the port 96 by a spring 98 confined between said valve and a collar threaded into the recessed portion of the closure, this valve being adapted to be unseated by a reduction of pressure in the container.

In assembling the pump and container the pump mechanism is first assembled when the tubular stud 36 is connected to the pump by means of the dished plate 61. The

pump is then connected to the container or casing section 22 by inserting the stud 36 connected to the pump through the opening 29 connected thereto in liquid tight connection by soldering around the edges of the opening 29. The intake is then assembled upon the tubular stud 36 when the container sections are connected and secured together as by soldering with the reduced and shouldered end of the stud 36 engaging in an axial opening in the casing section 21 and fixed therein by riveting said reduced end at the outer side of the casing section 21 and soldering.

In Figure 21 I have shown a modified structure of nozzle to connect the orifice of the discharge nozzle with the chamber in the casing 52 to permit of the flow of the liquid from such chamber and the nozzle orifice without obstruction by the valve spring 80, and a modification of the valve mechanism to control the flow of liquid from the tube 57 to the forward end of the pump cylinder and the discharge of the liquid from the opposite end of the cylinder through tube 71 to the chamber in the casing 52. To permit of the free flow of liquid unobstructed by the spring 80 from the casing chamber to the orifice of the nozzle the one end of the spring is seated upon an annular seat of a portion of the nozzle extending into the casing chamber, as shown at 52^b, said projecting nozzle portion having radial slots 52^a cut therethrough to maintain the casing chamber open to an enlargement of the nozzle orifice permitting the flow of the liquid from the casing chamber to the nozzle orifice outside of the spring without the necessity of passing through the spring as is the case in a structure as shown in Figure 3. To connect the tube 57 with the piston cylinder in front of the piston and to connect the tube 71 with the chamber of the casing 52 plugs 102 and 102' are secured in openings in the piston cylinder to extend laterally therefrom and from the casing, said plugs having angular plugs therein in communication with the recess 76 and the port 72 in the casing 52 and to which ports of the plugs the tubes 57 and 71 are connected as clearly shown. To control the connection of the tube 57 with the recess 76 communicating with the piston cylinder in front of the piston a ball valve 82^a is provided which is adapted to co-operate with a valve seat arranged at the end of the port in the plug in communication with the recess 76. It will be noted that when the liquid is being discharged from in front of the piston the pressure of the liquid on the valve through the recess 76 will operate to seat the valve 82^a and shut off the piston cylinder from the tube 57, and that such ball will be readily unseated by the suction of the piston as the latter is moved outward from the piston cylinder to permit the drawing of liquid to in front of the piston through the tube 57, there being sufficient space between the seat for the ball 82^a and the recess 76 to permit of the flow of the liquid past the ball to the recess 76 and the piston cylinder. The discharge of the liquid from back of the piston through the tube 71 to the chamber in the casing 52 is controlled by a ball valve 82^b adapted to co-operate with a valve seat formed at the connection of the bore of the plug 102' to control the connection of the tube 71 with the chamber of the casing 52. To connect the tube 71 with the casing chamber when the liquid is being discharged from the piston cylinder in back of the piston and to permit the ball valve 82^b to be unseated and maintain open communication between the bore of the plug 102' and the port 72 of casing 52, an elongated recess 72' is provided in the outer wall of the casing to intersect the port 72. This recess will permit the ball to be sufficiently moved from its seat by the pressure of the liquid coming through tube 71 to permit the flow of liquid past the ball through the recess 72' and port 72 to the casing chamber. The discharge of the liquid to the casing chamber from in front of the piston is controlled through the valve 76, which is constructed and operates in a manner as and for the purpose hereinbefore set forth, the pressure of such liquid as it is discharged into the casing chamber, due to the restricted area of the discharge orifice of the nozzle combined with the suction of the piston during this movement of the same, operating to maintain the valve 82^b seated shutting off communication between the casing chamber and the tube 71. The valve 76 is also arranged with the reduced portion 81 to cooperate with the valve seat at the inner end of the discharge orifice of the nozzle when the piston is in its innermost position to close such orifice.

Variations may be resorted to within the scope of my invention, and portions of the invention may be used without others.

Having thus described my invention I claim:

1. The combination of a cylindrical liquid carrying container having an outlet axially thereof, and an intake from the container connected to said outlet with the inlet to lie near the side of the container and having rotative movement on the axis of the container and transversely of the container to position by gravity the inlet to said intake near the side below the axis of the container and near the end which is lowermost.
2. The combination of a relatively flat liquid carrying container having an outlet centrally at one end, and an intake to the outlet from the container rotatably supported at one end on the axis of the container in communication with the outlet

and an inlet to the other end, said intake being constructed and arranged to position the inlet end by gravity near the side and either end portion of the container which 5 is lowermost for the purpose specified.

3. The combination of a cylindrical relatively flat liquid carrying container having an outlet centrally of one end, and an intake to the outlet from the container supported 10 to rotate on an axis in line with the outlet of the container and constructed and arranged to have movement transversely of said rotative movement and adapted to assume a position by gravity near the side portion and the end of the container which 15 is lowermost.

4. The combination of a cylindrical liquid carrying container, a reciprocable piston pump to extend transversely and diametrically 20 of the container, and rigid tubular intake means within and rotatable on the axis of the container in communication with the pump extending to adjacent the side of the container, said intake means being constructed and arranged to assume a position 25 by gravity below its axis of rotation with the free end near the side portion and either end of the container which is lowermost to connect the pump with the liquid in that 30 portion of the container which is lowermost in all positions thereof.

5. The combination of a cylindrical and relatively flat liquid carrying container; a reciprocable piston pump mounted to extend transversely and diametrically of the exterior of the container, said pump having suction inlets to opposite ends and a discharge outlet connected to opposite ends thereof; a tube connected at opposite ends 35 with the suction inlets and having a port intermediate the ends connected to the container centrally thereof; and a tubular intake rotatably supported at one end on the axis of the container in communication with 40 the port of the tube connected with the suction inlets and the other end extending to adjacent the side of the container, said intake being constructed and arranged to position the other end of the intake by gravity 45 with the inlet thereto near the side and end portion of the container which is lowermost in all positions thereof for the purpose specified.

6. The combination of a cylindrical and substantially flat liquid carrying container; a reciprocable piston pump mounted upon the exterior of the container to extend transversely and diametrically of the container, said pump having suction inlets to opposite ends and an outlet having valve connections with opposite ends thereof; means 55 to mount the pump upon the container and connect the suction inlets to the container centrally thereof, and a tubular intake connected at one end to the connection of the

suction inlets of the pump with the container and mounted to rotate about said connection as an axis and centrally of the container with the free end extending to adjacent the side of the container and arranged to position said end in the lowermost portion of the container in all positions thereof for the purpose specified. 70

7. The combination of a liquid carrying container; a piston cylinder having a chamber at one end with a discharge outlet and a port communicating with the end of the cylinder adjacent said chamber; a valve controlled outlet port from the end of the cylinder opposite to the chamber and connected to said chamber; suction inlets to opposite ends of said cylinder connected with the liquid in the container; a piston to reciprocate in the cylinder; and a valve in the chamber at the end of the cylinder operable during the reciprocation of the piston to alternately shut off and open communication between said chamber and the adjacent end of the cylinder and operable when the piston is in its innermost position 80 to close the outlet for the purpose specified. 85

8. The combination of a liquid carrying container; a piston cylinder having a connection with the liquid in the container; a piston reciprocable in the cylinder; a chamber at one end of the cylinder having an outlet and a port communicating with the adjacent end of the cylinder; and a valve in the chamber at the end of the cylinder operable during the movement of the piston in one direction to shut off communication between the cylinder and chamber and during the movement of the piston in reverse direction to open communication between the cylinder and chamber to eject the liquid from the cylinder to said chamber and discharge the same from the chamber outlet; and operable by the piston when the latter is in its innermost position to shut off communication between the outlet of the chamber and pump and thereby the container. 95 100 105

9. The combination of a liquid carrying container; a piston cylinder; a piston to reciprocate in said cylinder; suction inlets to the cylinder at opposite sides of the piston connected to the container centrally thereof; an intake from the container for the connection of the suction inlets with the container arranged to position the inlet to said intake in communication with the liquid in the lowermost part of the container in all positions of the latter; a chamber at one end of the cylinder having an outlet and a port communicating with the adjacent end of the cylinder; a valved connection between the opposite end of the cylinder and said chamber; a valve in the port between the chamber and the one cylinder end operable during the reciprocation of the piston to alternately open up and shut off communication between 110 115 120 125 130

such end of the cylinder and chamber, and operable by the piston when in its innermost position to co-operate with the outlet of the chamber to close the same; and means to lock the piston in its innermost position for the purpose specified.

10. The combination of a liquid carrying container; a piston cylinder having suction inlets to opposite ends thereof connected with the liquid in the container and a discharge outlet connected with opposite ends of the piston cylinder; a piston to reciprocate in said cylinder; a rod to reciprocate the piston extending from the end of the piston cylinder opposite to the discharge outlet; a valve operable during the reciprocation of the piston to alternately shut off and connect one end of the cylinder with the discharge outlet; and a valve operable 15 during the reciprocation of the piston to alternately shut off and connect the opposite end of the cylinder to said discharge outlet and alternately with the shutting off and connecting of the other end of the cylinder 20 with the discharge outlet; and said valve being operable by the piston when in its innermost position to close the discharge outlet for the purpose specified.

11. The combination of a cylindrical liquid carrying container having greater diameter than length; a piston cylinder extending transversely diametrically of the container and having inlet ports to opposite ends thereof connected to the container 25 and a discharge outlet connected to opposite ends of the cylinder; a piston to reciprocate in said cylinder; an intake in the container in communication with the connection of the inlet of the suction port of the cylinder 30 mounted to rotate on the axis of the container with the inlet end adjacent the side of the container and arranged to assume a position by gravity below the axis of the container and to position the inlet thereof near the end of the container which is lowermost; and a pair of valves operable by the reciprocation of the piston to connect the inlet ports 35 at opposite ends of the cylinder with the container and alternately connect opposite ends of the cylinder with the discharge outlet, and one of said valves being operable by the piston when in its innermost position to close the discharge outlet for the purpose specified.

12. The combination with a liquid carrying container, of a reciprocable piston pump to eject the liquid therefrom having a chamber with a discharge outlet and a port communicating with the pump cylinder; a valve in said chamber normally urged to position to close the port and operable by the movement of the pump piston in one direction to open said port to discharge liquid from the pump cylinder to said chamber, and operable by the piston when in its innermost

position to shut the outlet of the chamber for the purpose specified.

13. The combination with a liquid carrying container, of a reciprocable piston pump to eject the liquid from said container, having a chamber at one end with a discharge outlet and a port communicating with the pump cylinder; a tubular valve in said chamber slidably mounted in the port with the end within the chamber closed and having lateral ports communicating with the opposite end opening into the pump cylinder, said valve being normally urged to position and arranged to shut off communication between the chamber and pump cylinder through said port, said valve being operable by the liquid in front of the piston when the latter is moved into the pump cylinder to open communication between the pump cylinder and chamber through the lateral ports of said valve, and said valve being constructed and arranged to be moved by the pump piston when the latter is moved to its innermost position to close the discharge outlet of the chamber.

14. The combination of a liquid carrying container; a cylinder pump mounted on the exterior of the container to extend transversely and centrally of the container and adapted to eject the liquid from the container; and a plate fixed to the container to engage at the outer side of the pump to shield the pump and arranged to releasably engage a support for the purpose specified.

15. The combination of a liquid carrying container of greater diameter than length and having a depressed portion at one end extending transversely of the axis of the container; a cylinder pump mounted in said recess of the container operable to eject liquid from the container; and a shield fastened to the container at the outer side of the pump and arranged for the engagement of supporting means for the purpose specified.

16. The combination of a liquid carrying container having an outlet, and an intake to said outlet from the container comprising a rigid tubular member rotatably supported axially of the container and in open communication with said outlet and a second rigid tubular member having a universal connection at one end with the first member and in open communication therewith with the free end extending to adjacent the side of the container and adapted to be variously positioned at the side and either end of the container below the axis thereof.

17. The combination of a liquid carrying container having an outlet, and an intake to said outlet from the container comprising a rigid tubular member connected to the outlet and supported to rotate about the axis of the container, a hollow block supported by said tubular member to rotate

about an axis parallel with the axis of rotation of said member and in liquid connection therewith, and a second rigid tubular member carried by the block to rotate on an axis transverse to the axis of rotation of the first member and in liquid connection with said block for the purpose specified.

18. The combination of a cylindrical liquid carrying container of greater diameter than length and having an outlet axially thereof; and an intake from the container to said outlet comprising a rigid tube, means to support said tube to rotate about the axis of the container and connect the same to the outlet, a second rigid tube; and means to connect said latter tube at one end in fluid connection with the first tube and to have universal movement about said connection relative to the first tube with the opposite end open and adapted to assume a position near the side and end of the container which is lowermost in all positions of the latter.

19. The combination of a liquid carrying container having an outlet; a piston chamber having a discharge outlet at one end mounted upon the exterior of the container; a piston; a rod to reciprocate the piston extending from the end of the piston chamber opposite the outlet; suction inlets to opposite ends of the piston chamber connected with the outlet of the container; a valve controlled outlet from one end of the chamber connected to the discharge outlet; an

outlet from the opposite end of the chamber connected to the discharge outlet; and a valve to control the discharge of liquid from said outlet, said valve being operable when the piston is in its innermost position to close the discharge outlet for the purpose specified.

20. The combination of a liquid carrying container having an outlet; a piston cylinder having a discharge outlet mounted upon the exterior of the cylinder and having inlet ports to opposite ends thereof; a reciprocable piston in the cylinder; a tube connected at opposite ends with the inlets of the piston cylinder and having a connection between said inlet connections with the outlet of the container, valves to control the connection of said tube with the inlets of the piston cylinder; an outlet from one end of the cylinder; a tube to connect said outlet with the discharge outlet of the cylinder; a valve to control said connection of the cylinder with the discharge outlet; an outlet from the opposite end of the cylinder connected to the discharge outlet; and a valve to control said latter connection of the cylinder with the discharge outlet operable when the piston is in its innermost position to close the discharge outlet.

Signed at the city of New York, in the county of New York and State of New York, this 20th day of January, 1921.

PETER L. WILBUR.
